UNITED STATES PATENT OFFICE.

LEWIS B. DOMAN, OF EAST SYRACUSE, NEW YORK, ASSIGNOR TO THE AMPHION PIANO
PLAYER COMPANY, A CORPORATION OF NEW YORK.

PNEUMATIC SELECTIVE DEVICE.

1,258,399.

Specification of Letters Patent.

Patented Mar. 5, 1918.

Application filed August 7, 1915. Serial No. 44,262.

To all whom it may concern:

Be it known that I, LEWIS B. DOMAN, a citizen of the United States of America, and resident of East Syracuse, in the county of 5 Onondaga, in the State of New York, have invented new and useful Improvements in Pneumatic Selective Devices, of which the following, taken in connection with the accompanying drawings, is a full, clear, and 10 exact description.

This invention relates to a pneumatic selective apparatus for selecting and operating any one or more of a relatively large number of pneumatics or translating devices, 15 and is particularly useful in cooperation with the note sheet and tracker bar of a self-playing musical instrument in causing solo parts of a musical composition to be played with greater emphasis or force than the remaining parts.

It is evident, however, that the selective apparatus may be used in playing different instruments and in many other relations where it is desired to operate a considerable 25 number of pneumatic or other devices one by one or in combinations of two or more.

The broad object is to provide simple, practical and efficient means for selecting and operating any one or more of a relatively 30 large number of pneumatics or translating devices through the medium of a comparatively small number of selective units.

One of the specific objects is to provide a 35 selective apparatus which may be used in connection with a pneumatic self-playing musical instrument, such as a piano or other keyboard player, and operated through the medium of a relatively small number of 40 extra tracker ducts and corresponding rows of perforations in the note sheet to cause solo parts to be played with greater force or emphasis than the remaining parts.

Other objects and uses relating to specific 45 elements of the selective apparatus will be brought out in the following description.

In the drawings—

Figure 1 is a perspective view of my improved selective apparatus as used in connection with a pneumatic self-playing piano or other keyboard instrument, a portion of the note sheet and tracker bar being shown in section.

Fig. 2 is a transverse sectional view of

the selective apparatus taken on line 2—2, 55 Fig. 1.

Fig. 3 is an enlarged detail sectional view of a portion of the same apparatus taken in a plane centrally through one of the spring valves showing the means for opening such valve.

Fig. 4 is an enlarged vertical sectional view of the pneumatic player action taken on line 4—4, Fig. 1.

Figs. 5 and 6 are horizontal sectional views taken, respectively, in the planes of lines 5—5 and 6—6, Fig. 2.

Figs. 7 and 8 are longitudinal vertical sectional views taken, respectively, in the planes of lines 7—7, Fig. 2 and 8—8, Fig. 3. 70

The selective apparatus shown is adapted to be used in connection with a seven octave or eighty-four note piano player and comprises a valve board —1— having a plurality of, in this instance seven, separate 75 valve chambers —2—, one for each octave, and an exhaust chamber —3— common to all of the valve chambers and connected to each by an exhaust port —4—, each valve chamber being provided with an atmosphere port —5— preferably co-axial with the corresponding exhaust port —4—.

Communication between each valve chamber —2— and the exhaust chamber —3— and also between the valve chamber and atmosphere is controlled by a valve —6— and primary pneumatic —7—, each valve being provided with an angular stem —8—, projecting through the exhaust port —4—, and normally resting upon its corresponding 90 primary pneumatic.

These primary pneumatics are located within the exhaust chamber —3—, one for each of the valves —6—, and together with said valves and atmosphere ports —5— are 95 located in a straight row near one side of the valve chest —1—, as shown more clearly in Figs. 1, 2, 5, 6 and 7.

Each of the primary pneumatics —7— is provided with a separate atmosphere duct 100 —9— which may be normally closed and opened at the proper time to cause the corresponding primary pneumatic —7— to operate the valve —8— so as to close the port —5— and open the port —4—, thereby establishing communication between the valve chamber —2— and exhaust chamber —3— and producing the same air tension in both 105

chambers, it being understood that any one of the valves may be similarly operated independently of the others, or in combinations of two or more, as may be necessary to produce the desired result.

Each of the valve chambers —2— contains a plurality of primary pneumatics —10—, each communicating with a separate atmosphere duct —11— which is normally closed, but may be opened at the proper time to dis-tend the corresponding pneumatic and cause the operation of the plunger —12—.

These plungers —12— rest upon their corresponding pneumatics —10— and are pro-vided with stems —13— which are guided in suitable openings in the upper side of the valve chamber, as shown more clearly in Fig. 3, and may be utilized to operate various kinds of devices, an example of which will 20 be hereinafter described.

The exhaust chamber —3— may be connected by a pipe —14— to any suitable wind-inducing device or exhaust chamber capable of maintaining an air tension in said chamber normally different from that in the valve chamber so that when any one of the valves —6— is operated by its corresponding pneumatic —7— to open the port —4— and close the atmosphere port —5—, the air tension in the corresponding valve chamber —2— will instantly be the same as that in the exhaust chamber, but will not effect the operation of any one of the primary pneumatics —10— in that chamber until one or 35 more of such pneumatics is placed in communication with the atmosphere by opening one of the corresponding ducts —11—, whereupon the corresponding plunger or plungers —12— will be instantly operated to 40 produce the desired result, it being understood that each of the valves —6— controls the operation of all of the primary pneumatics —10— in the corresponding valve chamber —2—.

45 The valve chambers —2— extend in parallel lines transversely of the valve chest, and therefore the pneumatics —10— and corresponding plungers —12— of the several chambers are arranged in straight parallel 50 rows transversely of the valve chest and are also arranged in parallel rows lengthwise of the chest, each duct —11— being common to all of the primary pneumatics —10— of that particular lengthwise row.

55 It is now clear that the number of valve chambers —2— corresponds with the number of valves —6—, and therefore, each valve 6 controls a group of, in this instance four, of the primary pneumatics —10—.

60 In order to operate any one of the power-transmitting devices —12— of any one of the several groups, it is necessary to admit at-mospheric air to the pneumatic —7— cor-responding to that group, and to the primary 65 pneumatic of the particular power-transmit-

ting device which it is desired to operate. By these operations the valve chamber containing that particular group will be placed in communication with the exhaust chamber —3— by opening the adjacent port —4— 70 and closing the atmosphere port —5—, thus lowering the external pressure in the corresponding chamber —2— below atmospheric pressure so that when atmospheric air is ad-mitted to one or more of the primary pneumatics —10— in said chamber, it will cause the operation of the corresponding plunger 75 or plungers —12—.

In like manner any one or more of the plungers or power-transmitting devices 80 —12— of any group may be actuated to per-form some particular work, or any two or more of the primary pneumatics —7— may be brought into simultaneous co-action with any one or more of the primary pneumatics 85 —10— of the corresponding groups to effect the operation of the corresponding plungers or power-transmitting devices.

The term power-transmitting member 90 —12— is used in its broadest sense for im-parting motion or work to or upon other objects, and when combined in the manner described produces a complete pneumatic selective apparatus capable of operating as many parts as there are groups of primary 95 pneumatics —10— multiplied by the num-ber of pneumatics in each group, or the said devices may be operated in as many com-binations as it is possible to make from the 100 several groups.

The operation of the selective apparatus may be rendered automatic by the use of a tracker bar —A— and a perforated sheet —B— in which case the ducts —9— and —11— are connected to corresponding ducts 105 in the tracker bar to be controlled by perforations —9'— and —11'— in the traveling sheet or web —B—, it being understood that when no web perforations are registered with any of the ducts, the exhaust ports —4— will 110 remain closed by the valves —6— to pre-vent the operation of any of the primary pneumatics —10—. When it is desired to operate any one of the plungers 12 the web —B— will always be provided with at 115 least two corresponding apertures —9'— and —11'— arranged so as to register sim-ultaneously with the corresponding ducts —9— and —10—, the period during which the plunger is held in its operative position 120 depending upon the length or continuation of the apertures.

The web —B— and tracker bar —A— are shown as connected to a player action —C— of a pneumatic self-playing musical instru-ment, and for this purpose the tracker bar —A— is provided with a series of ducts —a— leading to the action and controlled by note perforations —b— representing a musical composition, and in order that the selec- 130

tive apparatus may be employed in causing the notes of any solo part to be played with greater force of emphasis than those of the remaining parts, the perforations —9— and —11— which are to emphasize those notes are arranged to register with the corresponding ducts at the same time that the solo perforations —b— register with their corresponding note ducts.

10 As illustrated more clearly in Fig. 4, the player action comprises a wind chest —15— having a plurality of separate but similar compartments —16— arranged side by side throughout the length of the wind chest, 15 there being one compartment for each of the plungers —12—. This wind-chest —15— is also provided with separate air chambers —17— and —18—, one above the other, and extending lengthwise of the wind chest, both 20 chambers 17 and 18 being common to all of the compartments —16—. The air chamber —17— has means as a pipe —19— for connection to a wind-inducing device or pumping bellows for maintaining a relatively high 25 air tension therein, while the chamber —18— is provided with means as a pipe —20— for connection with an expression-controlling device for maintaining a relatively low tension therein when desired, although it is evident that the air tension in the chamber 30 —18— may be varied.

Each of the compartments —16— is connected to the chambers —17— and —18—, respectively, by ports —21— and —22—, the 35 port —21— being provided with a valve —23— closing with the air tension in the chamber —17— and adapted to be opened by means of a primary pneumatic —24—, while the port —22— is provided with a 40 spring valve —25— opening with the air tension in the chamber —18— and adapted to close by the greater air tension in the corresponding compartment —16— when such compartment is connected to the high tension 45 chamber —17— by the opening of the valve —23— in a manner hereinafter described.

Associated with the wind chest —15— is a plurality of, in this instance three, valve shelves —26— arranged one above the other and running lengthwise of the wind chest, each valve shelf being provided with a plurality of exhaust chambers —27— corresponding in number to the number of 50 compartments —16— and connected to their corresponding compartments by passages —28—, each valve shelf being also provided with the same number of separate valve chambers —29— having corresponding exhaust ports —30— and atmosphere ports —31— leading, respectively, to the corresponding exhaust chambers —27— and to the atmosphere and controlled by corresponding valves —32—.

65 Each of the exhaust chambers —27— con-

tains a primary pneumatic —33— which is connected by a suitable pipe —34— and passage —35— to one of the note ducts —a— and serves to operate the corresponding valve —32— to open communication between the exhaust chamber —27— and valve chamber —29—.

Associated with each compartment —16— is a group of, in this instance three, striker pneumatics —36— mounted one above the other upon the under sides of the valve shelves —26— and communicating with the valve chambers —29— of their respective valve shelves through open passages —37—, there being as many groups of striker pneumatics as there are compartments —16—, each group corresponding to a different group of three specific notes of the musical scale.

It, therefore, follows that during the playing of a musical selection as controlled by the note sheet —B— and tracker ducts —a— when a note perforation of the note sheet is registered with any one of the ducts —a—, atmospheric air will be admitted 90 through the corresponding passages —35— and —34— to the primary pneumatic —33—, thereby inflating said pneumatic to operate the adjacent valve —32— for closing the atmosphere port —31— and opening the exhaust port —30—, thus establishing direct communication between the exhaust chamber —27— and corresponding striker pneumatic —36— through the valve chamber —29— and passage —37— and causing the 100 operation of the adjacent striker pneumatic to operate the corresponding key of the instrument.

In like manner, any one or more of the other striker pneumatics may be operated 105 with the same degree of force as determined by the degree of air tension in the chamber —18—.

It is evident, however, that if the air tension in the chamber —18— were less than the high tension normally existing in the chamber —17— and any one of the compartments —16— were placed in direct communication with the high tension chamber —17— by the opening of the valve —23—, 110 then the valve —25— would be instantly closed by the inequality of pressure at opposite sides thereof, thus producing substantially the same high tension in each of the exhaust chambers —27— of the particular 115 group associated with that compartment so that when any one of the corresponding valves —32— is opened, the adjacent striker pneumatic and corresponding key of the instrument will be operated with increased 120 force to emphasize that particular note.

The operation of the primary pneumatics —24— and valves —23— is controlled by the plungers —12— as follows:—The primary pneumatics —24— are connected by 130

separate conduits or pipes —38— to a corresponding number of atmosphere ports —39— in the upper side of the valve chest —1— of the selective apparatus, said ports —39— being normally closed by separate spring valves —40— extending across the upper ends of the stems —13— of the corresponding plungers —12— so that when any one of the plungers is lifted by the inflation of its primary pneumatic —10—, the corresponding valve —40— will be lifted from its port —39—, thereby opening said port to the atmosphere and causing the operation of the corresponding primary pneumatic —24— and its valve —23—.

It is now clear that if a musical selection is being played under a relatively low air tension or with subdued expression and the note sheet —B— is provided with the perforations —9'— and —11'— placed opposite the solo note perforations —b—, the corresponding striker pneumatics —36— will be operated with greater force than the remaining primary pneumatics as controlled solely by the note perforations, but it is equally evident that other parts of the musical composition may be similarly selected and played with increased force.

The three striker pneumatics of each group correspond to three adjacent keys of an octave on the theory that only one of the three keys of any group or similar group will be played at one and the same time, as otherwise it would produce discord, and for this reason I am able to emphasize any one or more of the notes of an eighty-four note player action by the use of only eleven extra ducts in the tracker bar and corresponding perforations in the note sheet to coöperate therewith,—that is the seven ducts —9— and the corresponding pneumatics —7— and valves —4— separately control seven octaves of keys on the keyboard, while the four ducts —11— coöperating with the ducts —9— separately control four groups of three different keys each, in each octave, each duct controlling a similar group in each of the seven octaves, and it, therefore, follows that any of the eighty-four notes may be automatically emphasized or played with increased force by the use of only eleven of the ducts —9— and —11— and corresponding perforations in the note sheet to register therewith simultaneously with the registration of the particular perforation representing the note which is to be emphasized.

After any one of the chambers —16— has been placed in communication with the high tension chamber —17— in the manner described and the tracker ducts —9— and —11— causing such communication have been closed by the note sheet, the corresponding primary pneumatic —24— controlling its valve —23— will be instantly cut off from communication with the atmos-

phere by the closing of the corresponding valve —40—, and at the same time said primary pneumatic will be placed in communication with the high tension chamber —17— through the small bleed hole shown in Fig. 70 4, and commonly used in primary pneumatics of this character.

This equalization of pressure at both sides of the primary pneumatic allows the valve —23— to be instantly closed by the suction 75 in the high tension chamber —17—, thereby cutting off communication between the two chambers —16— and —17— so that the tension in the chamber —16— will instantly become the same as that in the chamber —18— by the opening of the valve —25— in a manner previously described.

What I claim is:

1. In a pneumatic selective apparatus, the combination of an exhaust chamber and a 85 valve chamber having a connecting port, the valve chamber being provided with an atmosphere port, a valve controlling said ports and normally closing the exhaust port, a primary pneumatic in the exhaust chamber for operating the valve to open the exhaust port and to close the atmosphere port, a group of primary pneumatics in the valve chamber, and web-controlled means for operating the first-named primary pneumatic and any one of the other primary pneumatics simultaneously.

2. In a pneumatic selective apparatus, connected air chambers normally under unequal air tension, a valve normally closing 100 communication between said chambers, a primary pneumatic in one of the chambers for opening the valve, a group of primary pneumatics in the other chamber, and web-controlled means for operating the first-named primary pneumatic and one of the group pneumatics simultaneously.

3. In combination with a pneumatic action of a self-playing musical instrument, a group of primary pneumatics and separate devices actuated thereby and each controlling a plurality of action-units for modifying the tone of the corresponding notes, an additional primary pneumatic and means actuated thereby for controlling the action 110 of all of the group-pneumatics, and means for actuating the last-named pneumatic and one of the group-pneumatics to cause the tone-modifying operation of the action-unit of that group.

4. In a pneumatic selective apparatus, the combination with connected air chambers normally under unequal air tension, of a single valve normally closing communication between said chambers, a pneumatic actuator for opening the valve to equalize the tension in said chambers, a group of separate pneumatics all externally exposed to the variations of air tension in one of the chambers, and means for selectively admit- 120 125 130

ting air to any pneumatic of the group under a tension different from that externally thereto when the valve is opened.

5. In a pneumatic selective apparatus, the combination of a plurality of air chambers having normally open atmosphere ports and each containing a group of primary pneumatics, an exhaust chamber common to all of the first-named chambers and connected thereto by separate exhaust ports, separate valves controlling the ports of the first-named chambers and normally closing the exhaust ports, separate pneumatic actuators for said valves, and means for selectively and simultaneously operating any one of the primary pneumatics of any group and the pneumatic actuator corresponding to that group.

6. In a pneumatic selective apparatus, a plurality of groups of primary pneumatics and a corresponding number of controlling devices therefor, one for each group, each controlling device including a primary pneumatic and means for selectively and simultaneously operating any one of the primary pneumatics of the controlling devices and any one of the primary pneumatics of the corresponding group.

7. In a pneumatic selective apparatus, the combination of a plurality of separate air chambers each having a normally open atmosphere port and containing a group of primary pneumatics, an exhaust chamber common to all of the first-named chambers and connected thereto by separate exhaust ports, separate valves controlling said ports and each normally closing communication

between one of the first-named chambers and the exhaust chamber, separate pneumatic actuators in the exhaust chamber for operating the valves, and web-controlled means for selectively admitting atmospheric air to one of the pneumatic actuators and to one of the primary pneumatics of the corresponding group.

8. In combination with a pneumatic action of a self-playing musical instrument having its striker pneumatics divided into a series of groups and a corresponding number of separate air chambers, one for each group, a relatively low air tension chamber common to and normally communicating through separate passages with the group chambers, a relatively high tension air chamber common to and connected through separate ports with said group chambers, web-controlled pneumatic means for placing any one or more of the striker pneumatics in communication with the corresponding group chambers for playing a musical composition, an additional web-controlled pneumatic means for placing any one of the group chambers in communication with the high tension chamber for causing the particular pneumatic or pneumatics of that group which may be in communication with the same group chamber to be operated with increased force.

In witness whereof I have hereunto set my hand this 27th day of July, 1915.

LEWIS B. DOMAN.
